UNITED STATES PATENT OFFICE.

HARRY A. DOUGLAS, OF BRONSON, MICHIGAN.

CIRCUIT-CONTINUING DEVICE.

Application filed April 4, 1921. Serial No. 458,558.

To all whom it may concern:

Be it known that I, HARRY A. DOUGLAS, citizen of the United States, residing at Bronson, in the county of Branch and State 5 of Michigan, have invented a certain new and useful Improvement in Circuit-Continuing Devices, of which the following is a full, clear, concise, and exact description.

My invention relates to circuit continuing devices and has a number of objects and advantages in view. In accordance with one 10 of the characteristics of my invention one of two complementary contacts is preferably made hollow and has a carrier which surrounds a portion thereof, the hollow contact being in sliding engagement with this carrier, the engaging surfaces of the carrier and the hollow contact being non-circular to prevent the hollow contact from turning 15 within its carrier.

In accordance with another characteristic of my invention I employ a conductor which is surrounded by and is fastened to the hollow contact, the engaging surfaces of the 20 conductor and hollow contact being non-circular to prevent relative rotation therebetween.

Another feature of my invention resides in the employment of a substantially rigid 25 conductor electrically connected with one of the contacts, a spring pressing this contact into engagement with its complement, and a guiding element surrounding a portion of said conductor that is in sliding engagement with said guiding element, the engaging surfaces of said guiding element and conductor being non-circular to prevent relative rotation thereof.

One of the contacts is desirably connected 30 in circuit by means of two conductors that have overlapping ends, one of these ends of one conductor being provided with angular ears between which the other conductor is passed to obstruct relative turning movement of the conductors.

In the preferred embodiment of the invention there are several angular ears arranged in a circular row to afford a plurality of spaces in any one of which the other 35 conductor is receivable to obstruct relative turning movement of the conductors, the end of the conductor enclosed by these ears being enlarged to exceed the space between adjacent ears to prevent separation of the conductors by their relative longitudinal movement. An assembling bolt is employed

which is concentric with the circular row of angular ears and which passes through the conductors to hold them in selected relations, angular or otherwise, which is defined by 60 the ears between which the conductor having the enlarged end happens to be passed. Another conductor may also be clamped between and positioned by adjacent ears.

I will explain my invention more fully 65 by reference to the accompanying drawing in which Fig. 1 is a longitudinal view, partially in section and partially in full elevation, of a circuit coupler equipped in accordance with the preferred embodiment 70 of the invention; Fig. 2 is a view taken at right angles to the direction in which Fig. 1 is taken showing parts in section and parts in elevation; Fig. 3 is a longitudinal view of a part of a modification 75 of the structure shown in Figs. 1 and 2; Fig. 4 is a sectional view on line 4-4 of Fig. 3; Fig. 5 is a perspective view of overlapping conductors which are shown 80 separated in this figure; and Fig. 6 is a perspective view showing one of the contacts of the device.

Like parts are indicated by similar characters of reference throughout the different 85 figures.

The circuit continuing device shown includes a metallic shell 1 formed at one end with bayonet slots 2 having bayonet seats 3 formed therein. The base 4 of an incandescent lamp 5 is shown assembled 90 with the shell 1 by means of the bayonet pin 6 upon the lamp base, these pins being passed through the bayonet slots 2 into engagement with the bayonet seats 3. In the 95 form of the invention illustrated the circuit continuing device is a so-called "single pole" structure in which the lamp base is provided with a metallic sheath that constitutes one terminal of the lamp filament and electrically contacts with the metallic shell 1 that is included in grounded circuit with 100 the source of current. The other terminal of the lamp filament is a contact 7 that is upon the inner face of the lamp base and engages the contact 8. This contact 105 8 includes a hollow thimble shaped metallic member 9 which is coupled with a flat substantially rigid conductor 10 whose inner end is riveted to the end wall of the contact member 9 to constitute a supplemental 110 part thereof. Contact member 9 is surrounded by an insulating contact carrier 11

held in fixed assembly with the shell 1 by any suitable means such, for example, as the clamping ears 12 struck inwardly from the shell into holding engagement with the carrier. The conductor 10 is preferably flat and oblong in cross section and is further assembled with the contact member 9 by being received in grooves 13 formed within the contact member 9 on diametrically opposite sides thereof. These grooves prevent relative turning movement of the contact member 9 and the conductor 10, the riveting at the inner end of said conductor also taking part in preventing relative turning movement of the conductor and contact member. Grooves 13 are desirably formed by pressing the metal of the contact member 9 outwardly whereby external ribs 14 are also formed upon said contact member. These ribs serve as splines to permit the contact member to move within the contact carrier 11 without turning with respect thereto, said contact carrier conforming in shape to the rib portion of said contact member that is in sliding engagement with the carrier where surrounded thereby.

The outer end of the hollow contact member 9 is desirably formed with a flange 15 to afford a broad area of engagement for the inner end of the coiled spring 16 which surrounds the conductor 10. The outer end of this spring engages a guiding element 17 which is preferably in the form of a disc which is fixed in an end of the shell 1. The conductor 10 is in sliding engagement with this guiding element that is formed with an oblong opening conforming to the cross sectional area of said conductor which is thus prevented from turning with respect to the guide whereby the turning of the hollow contact member 9 is further guarded against. I prefer the particular forms of non-circular contours of the conductor 10 and hollow contact element 9 which are illustrated but I do not wish to be limited thereto, nor do I desire to be limited to the hollowness of contact 9.

The form of the invention illustrated in Figs. 3 and 4 is generally similar to that illustrated in Figs. 1 and 2, similar parts being given similar characters of reference. In the construction of Figs. 3 and 4 there are two hollow contact members 9 which are engageable with two contacts that are then provided upon the inner face of the lamp base which need not be provided with a metallic sheath as the shell 1 would not then be included in the electrical circuit.

The conductor 10 has its outer end formed into a circular enlargement which carries several angular ears 18 that define a plural-

ity of spaces 19 between which a substantially rigid conductor 20, complementary to the conductor 10, may be received. The conductor 20 has an enlarged circular end 21 which conforms in diameter to the diameter of the circle circumscribed by the ears 18. The unenlarged portion of the conductor may be received in the space between any pair of adjacent ears 18, these ears serving to prevent the rotation of the conductor 20. Openings 22 and 23 are formed in the overlapping ends of the conductors, these openings being co-axial and concentric with the circular space circumscribed by the ears 18. An assembling bolt 24 has its stem in threaded connection with the outer end of the conductor 10 and serves to clamp the conductor 20 into assembly with the conductor 10, a metallic washer 25 being preferably interposed between the overlapping ends of the conductors. These washers 25 may themselves be the enlarged ends of other conductors 26. The outer end of each conductor 20 may be formed into a split clamping ring 27 to enclose and grip the serving 28 surrounding the circuit wire 29. The serving is removed from the extreme end of the wire 29 which is clamped between the conductor 20 and the ears 30 integrally formed with said conductor. The conductors 26 may have formations 27', 30' similar to the parts 27 and 30 and provided for a similar purpose.

Characteristics not herein claimed will form the subject matter of a division of this application.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

A circuit continuing device having two complementary contacts one of which is hollow, the hollow contact having a longitudinal portion which is pressed outwardly to form an external rib and an internal groove; a conductor assembled with said hollow contact within said groove; a carrier for and surrounding and conforming in shape to the ribbed portion of said hollow contact that is in sliding engagement with the carrier; and a spring for pressing the hollow contact against its complement.

In witness whereof, I hereunto subscribe my name this 30th day of March A. D. 1921.

HARRY A. DOUGLAS.
